UNITED STATES PATENT OFFICE.

WILLIAM BARRY, OF PORTLAND, CONNECTICUT, ASSIGNOR TO THE NEW ENGLAND
ENAMELING COMPANY, OF MIDDLETOWN, CONNECTICUT, A CORPORATION.

DESIGN FOR A HANDLE FOR COOKING-POTS, DISH-PANS, OR SIMILAR ARTICLES.

54,302.

Specification for Design.

Patented Dec. 23, 1919.

Application filed May 1, 1916. Serial No. 94,835. Term of patent 14 years.

To all whom it may concern:

Be it known that I, WILLIAM BARRY, a citizen of the United States, residing at Portland, in the county of Middlesex and State of Connecticut, have invented a new, original, and ornamental Design for a Handle for Cooking-Pots, Dish-Pans, or Similar Articles, of which the following is a specification, reference being had to the accompanying drawing, forming part thereof.

Figure 1 is a front elevation of my improved handle for cooking pots, dish-pans or similar articles.

Fig. 2 is a rear elevation of the same.

Fig. 3 is a side elevation of the same, the side wall of a cooking pot being indicated by broken lines.

Fig. 4 is a sectional view on the line $x-x$ of Fig. 2.

I claim:

The ornamental design for a handle for cooking pots, dish-pans, or similar articles as shown.

WILLIAM BARRY.
